(57) CLAIM

The ornamental design for the golf tee, as shown and described.

DESCRIPTION

FIG. 1 is perspective view of the golf tee showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an elevational view showing the golf tee in use. The broken line showing of the golf ball and ground is included for the purpose of illustrating the environment of the design and forms no part of the claimed design.
